CLAIM

The ornamental design for a sphygmomanometer, as shown and described.

DESCRIPTION

FIG. 1 is a perspective view of a sphygmomanometer showing our new design:

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof;

FIG. 7 is a left side elevation view thereof;

FIG. 8 is a sectional view thereof taken along line 8—8 of FIG. 2;

FIG. 9 is a perspective view thereof with an armband shown in an opened position;

FIG. 10 is a front elevation view thereof;

FIG. 11 is a rear elevation view thereof;

FIG. 12 is a top plan view thereof;

FIG. 13 is a bottom view thereof;

FIG. 14 is a right side elevation view thereof;

FIG. 15 is a left side elevation view thereof; and,

FIG. 16 is a sectional view thereof taken along line 16—16 of FIG. 14.

The broken lines shown in FIGS. 1—16 are for illustrative purposes only and form no part of the claimed design.
